[57] **CLAIM**

The ornamental design for a flashlight, as shown and
described.

DESCRIPTION

FIG. 1 is a side elevational view of a flashlight showing our
new design, with the movable plug in folded position;

FIG. 2 is a top plan view of the flashlight shown in FIG. 1;

FIG. 3 is a bottom plan view of the flashlight in FIG. 1;

FIG. 4 is a front elevational view of the flashlight in FIG. 1;

FIG. 5 is a rear elevational view of the flashlight in FIG. 1;

FIG. 6 is a side elevational view thereof, showing the
movable plug in the upright open position; the other side
being a mirror image;

FIG. 7 is a top plan view of the embodiment depicted in FIG.
6; and,

FIG. 8 is a perspective view of the flashlight seen from the
top and one side.
